UNITED STATES PATENT OFFICE.

GEORGE C. BESSONET, OF CHICAGO, ILLINOIS.

MUSIC-HOLDER.

1,313,055.

Specification of Letters Patent.

Patented Aug. 12, 1919.

Application filed January 11, 1916. Serial No. 71,455.

To all whom it may concern:

Be it known that I, GEORGE C. BESSONET, a citizen of the United States, and a resident of the city of Chicago, county of Cook, and

5 State of Illinois, have invented certain new and useful Improvements in Music-Holders, of which the following is a specification.

My invention relates to improvements in music holders, and has for its object the provision of an improved construction of this character which is capable of exhibiting successively sheets of music or the like and which is easily operable and efficient in use.

10 The invention consists in the combinations and arrangements of parts hereinafter described and claimed.

The invention will be best understood by reference to the accompanying drawings forming a part of this specification, and in 20 which,

Figure 1 is a face view of a construction embodying my invention,

Fig. 2, a similar view with portions removed to show the interior working parts,

25 Fig. 3, a horizontal section taken through the construction,

Fig. 4, a vertical section taken through the construction, and

Fig. 5, an enlarged partial vertical section 30 taken through the construction and illustrating more particularly the reversing mechanism employed therein.

The preferred form of construction, as 35 illustrated in the drawings comprises a suitable casing 6 having removable face or cover portions 7, 8 and 9 giving access to the interior thereof. Guides 10 and 11 are positioned on cover member 7 to constitute guides for the edges of a continuous strip of 40 paper 12 wound upon a detachable spool or roller 13 and passing across the face of cover member 7 and windable onto a permanently mounted spool or roller 14, as will be readily understood. The strip 12 is printed with 45 the successive pages of a piece of music or the like, said pages being arranged transversely with respect to the length of said strip with the tops of the pages corresponding with the upper edge of said strip so 50 that as said strip is moved across the cover plate 7 from right to left in Fig. 1, the successive pages of music will be successively presented to view, as will be readily understood.

55 The detachable roller 13 is operated through the medium of a bevel gear 15

meshing with a bevel gear 16 on the end of a longitudinally shiftable shaft 17, said shaft carrying at its other end a bevel gear 18 adapted to intermesh with a bevel gear 19 60 for driving permanent roller 14 upon longitudinal shifting of said shaft. The shaft 17 is operated through the medium of an elongated gear 20 meshing with a pinion 21 on a shaft 22 driven by a bevel gear 23 from a 65 crown gear 24 operable through the medium of a spring 25 of any usual or desired form of clock spring mechanism, as will be readily understood. The usual winding stem 26 is provided for winding up spring 25. Up- 70 standing stop pins 27 are arranged on gear 24 and coöperate with a spring held stop plunger 28 operable by means of an operating lever 29. The pins 27 are so positioned and the other parts arranged so that upon 75 momentary withdrawal of plunger 28, the crown gear 24 is released and will operate through an arc of a circle until the next pin 27 encounters the plunger 28. With gear 18 shifted into mesh with gear 19 this partial 80 rotation of crown gear 24 will effect operation of roller or spool 14 to cause feeding of the strip 12 to present the first page of music thereon. After this subsequent operations of lever 29 will effect presentation of the suc- 85 cessive pages of music printed on strip 12 and automatic stopping of the same in central position on cover member 7, as will be readily understood.

At one end the elongated gear 20 is pro- 90 vided with an annular groove 30 engaged by a pin 31 on an operating lever 32 project- 95 ing through a slot 33 in cover plate 7. A latching lever 34 is provided with notches 35 and 36 arranged to be swung into engage- 100 ment with lever 32 when said lever is shifted into position to bring gear 16 or 18 into operative engagement with the corresponding gear 15 or 19 as the case may be. By this arrangement when all of the pages of the 105 piece or pieces of music have been successively presented as explained above, the shaft 17 is shifted to the right, as indicated in Fig. 2, to bring gear 16 into mesh with gear 15 and lever 29 withdrawn and held in 110 withdrawn position, whereupon spring 25 will operate to effect continuous rewinding of the strip 12. Then the roller or spool 13 may be removed and another roller bearing different pages of music or the like may be substituted therefor, as will be readily un- 115 derstood.

Spring operating brakes 37 and 38 are secured respectively to the under sides of cover members 8 and 9 in positions to offer resistance to the rotations of rollers 14 and 13 respectively. Each of these brake members coöperates with a corresponding bell crank lever 39 and 40 respectively, and operating pins or arms 41 and 42 are arranged on shaft 17 to coöperate with said bell cranks and whereby shifting of said shaft to the right causes release of the braking pressure of brake member 38 and application of braking pressure by brake member 37. Likewise shifting by said shaft to the left causes release of the brake member 37 and application of the brake member 38. It will also be observed, that the arrangement is such that in each instance the braking resistance is applied to the roller which is at the time 20 unwinding thus preventing spinning of said roller and insuring a tight and neat winding thereof upon the roller which happens at the time to be the active or winding roller.

The casing 6 is also provided with two 25 adjustable supporting legs 43 having rubber feet or rests 44 adapted to support the casing on the usual music rack of a piano, said legs being rendered adjustable by means of binding nuts 45 operating through longitudinal slots therein, as will be readily understood. The casing 6 is also equipped with a suspending member 46 having a securing foot 47 adapted to be secured to the upper portion of the piano and thus serve as 35 a means for securing the casing in place and preventing accidental displacements thereof.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and 45 modifications as come within the scope of the appended claims.

Having described my invention what I claim as new and desire to secure by Letters Patent is:

50 1. A device of the class described comprising a casing; two rollers mounted on said casing; a continuous strip of flexible material wound on one roller and windable onto the other roller; a bevel gear arranged to operate each of said rollers; a longitudinally

shiftable shaft carrying bevel gears arranged to be shifted into mesh with either of the roller-driven bevel gears; a clock spring mechanism; a gear operable by said clock spring mechanism; pins projecting from the face of said gear; a spring-held plunger arranged to engage said pins to prevent rotation of the gear carrying the same; and an operative connection between said pin-carrying gear and said longitudinally 65 shiftable shaft, substantially as described.

2. A device of the class described comprising a casing; two rollers mounted on said casing; a continuous strip of flexible material wound on one roller and windable onto the other roller; a bevel gear arranged to operate each of said rollers; a longitudinally shiftable shaft carrying bevel gears arranged to be shifted into mesh with either of the roller-driven bevel gears; means for 70 operating said longitudinally shiftable shaft; and brake mechanism for each of said rollers, automatically operable by longitudinal shifting of said longitudinally shiftable shaft to apply resistance to the unwinding 75 roller, substantially as described.

3. A device of the class described comprising a casing; two rollers mounted on said casing; a continuous strip of flexible material wound on one roller and windable on 80 the other, said strip being divided into pages; guides for said strip; a bevel gear arranged to operate each of said rollers; a longitudinally shiftable shaft carrying bevel gears arranged to be shifted into mesh with 85 either of the roller driving bevel gears; a clock spring mechanism; a crown gear operable by said clock spring mechanism; pins projecting from the face of said crown gear; a spring held plunger arranged to engage 90 said pins to prevent rotation of said crown gear; an operative connection between said crown gear and said longitudinally shiftable shaft; and a brake mechanism for each of 95 said rollers automatically operable by longitudinal shifting of said longitudinally shiftable shaft to apply resistance to the unwinding 100 roller, substantially as described.

In testimony whereof I have signed my name to this specification in the presence of 105 two subscribing witnesses.

GEORGE C. BESSONET.
